Des. 231,147
Patented Apr. 2, 1974

231,147

BAKERY TRAY OR THE LIKE

Charles F. Hinrichs, Bartlesville, Okla., assignor to
Phillips Petroleum Company

Filed Dec. 29, 1971, Ser. No. 213,805

Term of patent 14 years

Int. Cl. D3—99

U.S. Cl. D87—1 R

FIG. 2

FIG. 3

FIG. 4

FIG. 5

FIG. 6

FIG. 7

FIG. 8

FIG. 1 is a top perspective view of a bakery tray or the like showing my new design;

FIG. 2 is a fragmentary top plan view, the other one-half being like that shown;

FIG. 3 is a fragmentary bottom plan view, the other one-half being like that shown;

FIG. 4 is a side elevational view;

FIG. 5 is an end elevational view;

FIG. 6 is an enlarged sectional view taken on the line 6—6 of FIG. 2;

FIG. 7 is an enlarged sectional view taken on the line 7—7 of FIG. 2; and

FIG. 8 is a side elevational view showing a modified form of my new design wherein the only modification is the omission of the circular openings on each side.

I claim:

The ornamental design for a bakery tray or the like, as shown and described.
